United States Patent Office

Des. 192,882
Patented May 22, 1962

192,882

ELECTRIC ORGAN

Nels A. Miller, Oak Park, Ill., assignor to Hammond
Organ Company, Chicago, Ill., a corporation of Dela-
ware

Filed Jan. 30, 1961, Ser. No. 63,756

Term of patent 14 years

(Cl. D56—2)

Fig. 2

Fig. 1

Fig. 4

Fig. 3

FIG. 1 is a front elevational view of an electric organ showing my new design;

FIG. 2 is a right end elevational view thereof;

FIG. 3 is a top view thereof;

FIG. 4 is a vertical transverse sectional view through the upper portion of the organ, and may be considered as taken in the direction of the arrows substantially along the line 4—4 of FIG. 3; and

FIG. 5 is a perspective view thereof.

The back of the organ is plain, and the left side is the reverse complement of the side shown in FIG. 2.

I claim:

The ornamental design for an electric organ, as shown and described.
